CLAIM

The ornamental design for an air conditioning filter shell, as shown and described.

DESCRIPTION

FIG. 1 is a front, top perspective view of an air conditioning filter shell, showing my new design;

FIG. 2 is a rear, bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof; and,

FIG. 9 is a front, top perspective view of the air conditioning filter shell of FIG. 1 in an exploded and partially folded configuration.
